UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE FOR BOILERS.

1,268,826.

Specification of Letters Patent. Patented June 11, 1918.

Application filed July 31, 1917. Serial No. 183,730.

To all whom it may concern:

Be it known that we, JOHN ROGERS FLANNERY and ETHAN I. DODDS, citizens of the United States, and residents of Pittsburgh, 5 in the county of Allegheny and State of Pennsylvania, have invented certain new and useful Improvements in Stay-Bolt Structures for Boilers; and we do hereby declare the following to be a full, clear, and exact 10 description of the invention, such as will enable others skilled in the art to which it appertains to make and use the same.

This invention relates to improvements in stay bolt structures for boilers and more particularly to means to permit the testing of 15 said stay bolt,—the object of the invention being to provide simple and efficient means whereby the bolt may be easily tested to determine whether the same is ruptured and 20 without the necessity of having access to the bore of the bolt for this purpose.

With this object in view the invention consists in certain novel features of construction and combinations of parts as herein- 25 after set forth and pointed out in the claims.

In the accompanying drawing is illustrated an embodiment of our invention.

1 represents a stay bolt of the flexible type having a rounded head 2 at one end and 30 having its other end adapted for threaded connection with an inner boiler sheet 3. The bolt 1 is provided with a tell tale bore 4 which extends from the inner end of the bolt to and within the headed end 2 thereof. 35 The inner end of the bore 4 may be sealed by a plug 5 of fire clay or other suitable material and this plug holds in place a cup shaped cap 6 which may be of magnetic metal.

40 A rod 7 is disposed freely within the bore 4 and is of a length somewhat less than the distance between the metal cap 6 and the other end of said bore. The rod 7 is normally maintained in an intermediate position by means of springs 8 and 9 at respective 45 ends thereof. The spring 8 may bear at one end against the cap 6 and at its other end against one end of a tube or envelop 10 which incloses the rod 7. The spring 9 may bear at one end against the opposite end of said tube and at its other end against the end wall of the boiler.

The tube 10 is composed of absorbent ma-

terial and is of a diameter sufficient to approximately fill the bore 4. The absorbent 55 material of which the tube is composed may consist of readily absorbent paper, so that in the event of rupture of the bolt, water entering the bore 4 will cause said absorbent tube to expand sufficiently to prevent longitudinal movement of the rod 7.

Under normal conditions when the bolt is whole, and an electromagnet 11 having its coil included in an alternating current circuit, or in a circuit having an interrupter 65 included therein, is applied to the inner end of the bolt, the rod 7 will be caused to reciprocate and to strike the cap 6,—the sound thus produced indicating that the bolt is whole. Should the bolt become ruptured 70 so as to admit moisture to the bore 4 and thus cause the tube 10 to expand and thereby bind the rod 7 within the bore, the application of the magnet 11 would not cause the rod 7 to reciprocate and therefore said rod 75 could not strike the cap 6. There would therefore be no sound and this fact would denote that the bolt is ruptured.

Having fully described our invention what we claim as new and desire to secure by 80 Letters Patent, is:

1. The combination with a stay bolt having a bore, of a device confined and movable in said bore to provide an audible signal within the latter. 85

2. The combination with a stay bolt having a bore, of an audible signaling device within said bore, and means for preventing the operation of the signaling device when the bolt is ruptured. 90

3. The combination with a stay bolt having a bore, of a rod mounted to reciprocate in said bore, said rod being responsive to the action of a magnet applied to the bolt. 95

4. The combination with a stay bolt having a bore, of a member of magnetic material disposed in said bore, and absorbent material encircling said member.

5. The combination with a stay bolt having a bore closed at both ends, of a rod of 100 magnetic material disposed within said bore, a tube or envelop of absorbent material inclosing said rod and means normally spacing the ends of said rod from the closed ends of the bore. 105

6. The combination with a stay bolt hav-

ing a bore, of a member within said bore and normally adapted to reciprocate, said member being responsive to the action of a magnet, and means responsive to the action of moisture to prevent reciprocation of said member when the bolt becomes ruptured.

In testimony whereof, we have signed

this specification in the presence of two subscribing witnesses.

JOHN ROGERS FLANNERY.
ETHAN I. DODDS.
